ATTACHMENT UNIT FOR ACETYLENE TORCHES

Nils H. Christenson, Wyoming, Ohio

Application December 14, 1945, Serial No. 635,074

4 Claims. (Cl. 266—23)

1

This invention relates to an acetylene torch, and more particularly to an attachment unit adapted to be fitted to the torch whereby same may be manipulated about a pivot support for cutting described circles or ellipses in accurately curved lines. The attachment can also be used as a layout tool with or without the torch. One advantage of the attachment unit is that conventional torches may be used for cutting along accurate curved lines and do not need to be specially constructed. The attachment unit may be attached to any part of the torch, preferably to the nozzle, and can be used with a torch of a conventional or special design.

Generally described, the attachment unit comprises two arms pivoted together in the general form of a compass, with means for adjusting and securing the arms at any desired angle to each other. The free ends of the arms are each provided with an extension arm adjustably mounted as to length in a holder pivoted to the end of the arms. Means is provided on the extension member for securing the attachment unit to the torch, this preferably being a clamp for engaging the nozzle of the torch. The pivot preferably comprises a clamp screw and a winged head whereby the arm holders may be adjusted at any angle and clamped in adjusted position. The extension arm which is not clamped to the torch may be of different types so that they may be readily interchanged for different types of work being performed with the torch. This extension arm may be clamped in the arm holder by a clamp screw or some other device or it may be loosely mounted to be spring pressed when in use. The extension arm for holding the attachment to the torch or nozzle may be substituted with a chalk-holding arm whereby the attachment may be used independent of the torch for marking for layout work.

For a better understanding of the drawings reference is made to the accompanying drawings, in which:

Fig. 1 is a view of a torch handle with an attachment connected thereto embodying the invention;

Fig. 2 is a view of the attachment showing a substitute extension arm;

Fig. 3 is a side elevation view showing variation in use of the attachment with the substitute extension arm;

Fig. 4 is a side elevation of a chalk holding arm which may be used with the attachment; and

Fig. 5 is a side elevation of the head, nozzle and the collar or nut for attaching the head and nozzle together.

Referring specifically to the drawing in which like numerals are used to designate like parts, numeral 1 is a handle of a torch terminating on one end in arms 2 and 3 that connect with oxygen and acetylene supply lines which are attached to parts 4 and 5 at the opposite end of the handle.

2

A head 6 is pivotably connected to the arms by means of a nose 7 fitting therebetween and secured by a bolt 8 projecting through the arms of the handle and the nose of the head.

5 The head is preferably provided with screw threads 9 on a portion of its outer wall for receiving a collar connection 10 having screw threads 11 on its inner wall for engaging with those on the head. A portion of the wall of the collar connection is removed, and the end terminates in an inwardly extending flange 12. The removed portion of the collar permits the nozzle 13 to be inserted in the collar and have one end clamped tightly against the seat of the head. The nozzle is provided with a flange 14, and the flange 12 on the collar engages the flange 14 on the nozzle so that the flanged end of the nozzle may be clamped to seat against the end of the head. The head and nozzles are provided with passages 15 and 16 A and B communicating with the passages in the handle leading to supply lines attached to parts 4 and 5.

20 The attachment unit, denoted generally by numeral 15, comprises arms 16 and 17, pivoted together at 18, and an arcuate guide 19 fitted to one arm by a nut 20 screw threaded to the reduced end 21 of the guide. A shoulder 22 on the guide at the junction of the reduced end is impinged against a spring 23 which is attached to the arm 16 at 24. A screw 25 is associated with the other arm 17 in position to impinge against the guide 19 and secure the arms in any angular position to which they are adjusted.

25 Arms 16 and 17 are provided with rod holders 26 and 27 respectively pivoted to each. Holder 26 is pivoted to arm 16 by a bolt 28 screw-threaded to the socket and having a polygonal head to facilitate it being turned. The rod holder 26 is substantially U-shaped with rod 31 extending 30 therethrough and clamped by the sides of the U-shaped holder. The bolt extends through the end of arm 16 and the adjacent arm of the holder and into the opposite adjacent arm to which it is screw-threadedly connected. Thereby the single 35 bolt serves as the pivot connection for the arm and rod holder, and also for clamping the sides of the rod holder against the rod for holding same in place. Rod holder 27 is likewise attached to arm 17 by a bolt 30, except that rod holder 27 merely has a bore therethrough for reception of the rod and is clamped by another 40 means hereinafter described.

45 The end 32 of rod 31 is bent at a right angle to receive jaws 33 of a clamp between which the nozzle 13 is secured by a nut 34 on the bent end which compresses the jaws of the clamp between it and the right angle corner. This typifies any suitable clamping means provided on the attachment for securing same to the torch.

50 Rod 35, having bifurcated resilient ends 36 between which a piece of chalk 37 is adapted to be inserted, may be substituted in the rod holder in lieu of rod 31 in order that the device may be 55

used separately and independently of the torch for marking a described circle with the other rod serving as the center, the same as if the torch were used in the described circle. An annular sleeve 35a is loosely mounted on the rod 35 and can be moved towards or away from arms 36 for causing them to hold or release the chalk 37.

Rod 38 is secured to holder 27 by clamp bolt 39 having one end screw-threaded into the wall of the holder perpendicular to the longitudinal bore in which the rod is held for impinging against the rod and clamping same in the holder. The rod may be straight or bent to provide an intermediate offset portion 40 adjacent the pointed end 41 in order to provide additional means for regulating the diameter of circle to be described. It is especially suitable for permitting circles being described of larger or smaller diameter than would be permitted by the angular adjustment of the pivoted arms alone. The point 41 may be adjusted to as little as a fraction of an inch from the tip of the nozzle, and because of its proximity to the heat at the nozzle tip, the pointed end 41 is preferably of "stellite," a non-ferrous hard metal alloy.

Rod 42 is advantageously bent at one end at an angle to provide a support for one end of a spring 44 connected to it, the other end of the spring being connected to the attachment device, preferably to the end of the bolt 39. To facilitate attachment of the spring, the bent end of the rod may be advantageously grooved at 45 for seating the spring. When the rod is used with the spring, the bolt 39 will be released to allow free reciprocation of the rod in the holder and the pointed rod spring-pressed against the point of support. This rod is particularly useful for cutting ellipses, such as is required when branching pipe connections at odd angles in the sides or corners of rectangular tanks or in other pipes of the same or larger diameters.

The operator may easily and quickly use the attachment with the rod 42 fixed or resiliently held in the socket while operating the torch in a path described by the attachment.

The pointed end 46 of the right angle end of the rod may be employed as the pivot about which the torch is described in lieu of pointed end 41. The holder may be adjusted at the proper angle to permit the pointed end 46 to be brought into proper position. The adaptability of the device for this variation is generally illustrated in Fig. 3. The rod is especially adapted for this purpose where large circles are to be described which are much larger than would be permitted by the angular adjustment of the arms alone.

The nose 7 has medially of the wall of the recess in which bolt 8 is inserted an annular groove C with a passage leading to two openings D in opposite faces through which lubricating grease may be introduced through a longitudinal bore in the bolt.

One of the passages in the nozzle 13 connects with passages A, and the other passage in the nozzle connects with the passage B.

From the above description, it is apparent that the attachment lends itself to many and various adjustments, thereby permitting the use of torches on all different types of works. Cutting of holes, circles, ellipses and work of similar nature can, with the aid of the attachment, be used to do with torches what heretofore have required the use of machine tools. The attachment is readily fitted to any torch and permits the torch to be manipulated to cut accurately

and symmetrically along predetermined curved lines.

The rods herein described and shown for use with the attachment are illustrative of those which may be used. Others, differing in details of construction, may be used.

I claim:

1. A trammeler attachment unit for describing accurately curved lines about a pivot support with acetylene torches comprising arms pivoted together at one end, a rod holder pivotally connected at the free end of each arm, a socket in each of the holders, and a rod slidably adjustable in each of the sockets, means for securing the rods in adjusted position in the sockets, and clamp means on one of the rods for attaching the unit to an acetylene torch.

2. A circle-forming attachment for acetylene torches comprising arms pivoted together at one end to form a compass-like member, a rod holder pivotably connected at the free ends of each arm having a socket therein, an extension rod slidably adjustable in each of the sockets, means for securing the rods in adjusted position, and means on one of the extension rods for clamping the attachment to the nozzle of an acetylene torch.

3. An attachment unit for an acetylene torch comprising a rod for describing the torch in an orbicular path about a point of support, a compass-like member having the ends of two legs pivoted together with their opposite ends free, a holder pivoted to the free end of one of the legs in which said rod is freely reciprocable, spring means between said rod and unit to spring-press the rod against the point of support, a holder pivoted to the free end of the other leg, an extension rod carried by said second holder, and means carried by said second holder for attaching the unit to an acetylene torch.

4. An attachment unit for an acetylene torch comprising a rod for describing the torch in an orbicular path about a point of support, a compass-like member having the ends of two legs pivoted together with their opposite ends free, a holder pivoted to the free end of one of the legs of the member having the rod reciprocably mounted therein, means for holding the reciprocably mounted rod in position in the holder, a second rod pivotably connected to the free end of the other leg, and means for clamping the second rod to an acetylene torch.
